US0D1072042S

(12) **United States Design Patent** (10) Patent No.: **US D1,072,042 S**
(45) Date of Patent: ** Apr. 22, 2025

(54) **THERMAL PRINTER**

(71) Applicant: **Guofei Zhou**, Jiangsu (CN)

(72) Inventor: **Haihong Li**, Jiangsu (CN)

(**) Term: **15 Years**

(21) Appl. No.: **29/981,814**

(22) Filed: **Jan. 2, 2025**

(30) **Foreign Application Priority Data**

Nov. 27, 2024 (CN) 202430751795.4

(51) **LOC (15) Cl.** **18-99**

(52) **U.S. Cl.**

USPC **D18/19**

(58) **Field of Classification Search**

Primary Examiner — L. A. Grabenstetter

(57) **CLAIM**

The ornamental design for a thermal printer, as shown and described.

DESCRIPTION

FIG. 1 is a front, right and top perspective view of a thermal printer showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate portions of the thermal printer that form no part of the claimed design.

1 Claim, 8 Drawing Sheets
